UNITED STATES PATENT OFFICE

117,589

DESIGN FOR A COMBINED PIANO CASE,
RADIO, PHONOGRAPH, AND MUSIC CAB-INET

Jeanne Keenan Webster, Galveston, Tex.

Application June 29, 1939, Serial No. 85,764

Term of patent 14 years

To all whom it may concern:

Be it known that I, Jeanne Keenan Webster, a citizen of the United States, residing at Galveston, in the county of Galveston and State of Texas, have invented a new, original, and ornamental Design for a Combined Piano Case, Radio, Phonograph, and Music Cabinet, of which the following is a specification, reference being had to the accompanying drawing, forming a part thereof.

The drawing is a perspective view of the article showing my new design.

I claim:

The ornamental design for a combined piano case, radio, phonograph, and music cabinet, as shown.

JEANNE KEENAN WEBSTER.
